UNITED STATES PATENT OFFICE.

GEORGE H. MYRICK, OF CHICAGO, ILLINOIS, ASSIGNOR TO CAPITAL ELECTRIC COMPANY, OF CHICAGO, ILLINOIS, A CORPORATION OF ILLINOIS.

WASHING-MACHINE.

1,286,722.

Specification of Letters Patent.

Patented Dec. 3, 1918.

Application filed May 8, 1916. Serial No. 96,024.

To all whom it may concern:

Be it known that I, GEORGE H. MYRICK, a citizen of the United States, residing at Chicago, in the county of Cook and State of Illinois, have invented a certain new and useful Improvement in Washing-Machines, of which the following is a full, clear, concise, and exact description, reference being had to the accompanying drawings, forming 10 a part of this specification.

My invention relates to an improved form of washing machine wherein the articles to be washed are moved in the solution in which they are washed by a column of washing solution forcibly drawn or sucked through the fabrics and their container, which in the embodiment of my invention hereinafter described is in the form of a rotatable drum comprising a skeleton frame- 15 work covered with wire netting, or other suitable foraminous material.

In the hereinafter described embodiment of my invention the open work drum or fabric container is mounted for movement 25 around a horizontal axis in a tank or tub arranged to contain washing solution to a depth substantially immersing the drum or container. Mounted for rotation around a substantially vertical axis, disposed below 30 the container and immersed in the washing solution is what may be termed a fan or screw propeller provided with means for driving it and arranged when operated to draw or suck a column of washing solution through the fabrics to effect the cleaning thereof. The column of water thus initially sucked or drawn through the fabrics may be, and desirably is, subsequently directed 35 against and through the fabric container 40 through a passage or conduit communicating with the discharge side of the fan or propeller.

As will presently be described in more detail the fan or propeller is driven by an electric motor and the rotatable container or drum is either driven by the force of the column of washing solution drawn there-through, or is mechanically driven by the same motor as serves for the means for rotating the fan or propeller. The mechanical connections interposed between the motor and fabric container are such that the container or drum, at the will of the operator, is driven either against the force of the

column of washing solution drawn there-through by the propeller or in the direction of the flow of washing solution impelled by the suction of the propeller. 55

These and other features of my improved washing machine are fully set forth in the 60 following detailed description wherein reference is made to the accompanying drawings in which—

Figure 1 is a vertical sectional view of the washing machine of my invention. 65

Fig. 2 is a vertical sectional view thereof taken on the line 2—2 of Fig. 1, and

Fig. 3 is a horizontal sectional view taken on the line 3—3 of Fig. 2.

Similar characters of reference refer to 70 similar parts throughout the several views.

In the drawings 4 represents a tank or tub preferably constructed wholly or in part of sheet metal and suitably mounted upon an angle iron framework 5, the tank being 75 provided with a suitable removable cover 6 which may consist of two parts hinged one to the other, as illustrated. Disposed within the tank or tub 5 is a rotatable cylindrical fabric container or drum indicated at 7, 80 said drum or container comprising a pair of heads and a skeleton framework over which is stretched wire netting or other suitable open work material which constitutes the cylindrical surface of the drum. The 85 drum is desirably provided with a pair of doors 8—8 which may be opened to permit the insertion and removal of the articles to be washed. It will be noted that the drum or fabric container is mounted for rotation 90 around a substantially horizontal axis by means of trunnions or stub shafts journaled in the walls of the tank or tub 4. The front and rear walls of the tank are conformed to lie in immediate proximity to the cylindrical 95 surface of the fabric container 7 and the side walls of the tank are conformed to lie quite close to the heads of the container; therefore, it will be seen that water caused to circulate within the tank must necessarily take a path through the open work container and the fabrics therein contained. As is clearly shown in Fig. 1, the tank is capable of containing washing solution to a depth substantially immersing the fabric 105 container 7.

Supported by the machine framework 5 is an electric motor 9 the shaft 10 of which ex-

tends upwardly and is connected either directly or through an interposed clutch (not shown) with the shaft 11 of the fan or screw propeller 12, the shaft 11 having a suitable bearing in the bottom of the tank 7 and extending through a suitable packing box or gland 13. The motor 9 may be, and in practice desirably is, provided with a shield or cover to protect it, but for the purpose of clearness this shield has been omitted in the drawings. It will be noted that the motor shaft extends upwardly through a gear housing 14 and is provided with a worm 15 meshing with a worm gear 15^a, which worm gear is in turn fixed upon one end of a horizontal shaft 16 having a bearing in the housing 14, the other end of said shaft extending to one side of the machine framework and being there journaled in a second gear housing 17 where it is provided with a bevel pinion 18. The bevel pinion 18 is permanently meshed with a co-operating bevel pinion 19 mounted upon the lower end of a vertical shaft 20 which preferably extends through an inclosing tube or sleeve 21 and at its upper end bears in a gear and clutch housing 22. At its upper end the shaft 21 is provided with a bevel or miter gear 23 meshing with a pair of spaced bevel or miter gears 24 and 25, each of which is loosely mounted upon the adjacent stub shaft or trunnion of the fabric container. Each of the bevel or miter gears 24 is provided on that face nearest the gear 23 with suitable clutch teeth arranged to be engaged by a clutch member 26 splined upon the shaft or trunnion of the fabric container and movable into engagement with either one of the gears 24 and 25. The clutch member may, of course, be moved to a position wherein it engages neither of its associated gears 24 and 25. The operation of the clutch member is effected through a manually operated lever 27 pivoted to a bracket fixed on the machine framework and provided at its lower end with a fork arranged to engage in an annular slot in the clutch member in the usual manner. It will be understood that when the clutch member 26 lies midway between the gears 24 and 25 the fabric container is free to turn around its axis independently of the motor 9 and the driving mechanism interposed between the motor and the fabric container and, moreover, that when the clutch member is in engagement with the teeth of one of the gears 24 and 25 the fabric container is driven in one direction and when in engagement with the other gear in the opposite direction.

As is most clearly illustrated in Figs. 1 and 2 a baffle plate 28 extends across the bottom of the tank 7 and is spaced somewhat from the bottom of the tank to provide a conduit leading from beneath the fan or propeller to that side of the tank opposite the propeller. The baffle plate 28, which is de-

sirably formed of sheet metal, is, moreover, conformed to present a more or less cylindrical housing 29 within which the fan or propeller operates.

In making use of my improved washing machine after the fabrics have been placed within the container and the tank supplied with washing solution to substantially the depth illustrated in the drawings the motor 9 is operated in the direction indicated by the arrow whereupon the fan or propeller acts to draw or suck a continuous column of washing solution downwardly through the fabric container and the fabrics therein. This column of washing solution is forcibly driven through the conduit provided between the baffle 28 and the bottom of the tank and is projected upwardly from the discharge end of said conduit and again through the fabric container. Under some conditions it is desirable to permit the action of the propeller alone to effect the rotation of the fabric container. Under other conditions it is desirable to drive the fabric container in a direction opposed to the direction of the column of solution drawn toward the propeller and in some cases it is desirable to mechanically drive the fabric container in the direction of the stream of washing solution impelled by the propeller. Attention is directed to the fact that inasmuch as the walls of the tank or tub lie in immediate proximity to the fabric container practically all of the solution caused to take the paths indicated by the arrows is directed through the fabric container and consequently through the fabrics contained therein.

While I have illustrated, and desirably employ, a conduit of the type afforded by the baffle 28 I am aware of the fact that an operative machine may be constructed without utilizing the baffle 28 or a conduit the equivalent of the one heretofore described.

Having thus described my invention what I claim as new and desire to secure by Letters Patent of the United States is:

1. A washing machine of the class described comprising a rotatable openwork fabric container movable around a horizontal axis, a tank in which the container is mounted, said tank having its walls lying adjacent the cylindrical surface of the container and arranged to contain washing solution to a depth substantially immersing the container, a screw propeller mounted for rotation around a substantially vertical axis and disposed in the tank beneath the container, a motor for rotating the propeller in such direction that the latter draws a continuous column of washing solution downwardly through the container and the contents thereof, mechanical connections between the motor and the container, and means for operating on said connections to drive the container so that it opposes the

movement of washing solution set up by the propeller or moves in the direction of the flow of washing solution as desired.

2. In a washing machine of the class described the combination with a tank or tub, an open work fabric container journaled in said tank, said tank arranged to contain washing solution to a depth substantially immersing the container, a screw propeller, 10 immersed in the solution, disposed at one side of the container and mounted for rotation around a substantially vertical axis, a motor for driving the propeller in such a direction that it draws a continuous column 15 of washing solution through the container and the contents thereof, mechanical connections between the motor and fabric container, and means for operating on said connections so that the container is driven to either oppose the movement of washing solution 20 impelled by the propeller or moves in the direction of the flow of solution, as desired.

3: In a washing machine the combination with an openwork cylindrical fabric container movable around a substantially horizontal axis, a tank inclosing and supporting the container having its walls lying in immediate proximity to the cylindrical surface of the container and adapted to contain 25 washing solution to a depth substantially immersing the fabric container, a propeller disposed in the tank beneath the container and rotatable around an axis at right angles to the axis of the container and substantially 30 tangential to the cylindrical surface of the container, a conduit leading from beneath the propeller across the bottom of the tank and terminating beneath the container on the side of the tank opposite the propeller, 35 and a motor for rotating the propeller in such a direction that it draws a continuous column of solution downwardly through the container and forces it through the conduit and thence upwardly against and into the container, 40 mechanical driving connections between the motor and said rotatable fabric container, and a two-way clutch in said connections whereby the container may be driven around its axis in either direction simultaneously with the operation of the propeller.

5. A washing machine comprising in combination with a cylindrical openwork fabric container, a tank inclosing said container having its walls lying in immediate proximity to the cylindrical surface of said fabric container, said tank arranged to contain 50 washing solution to a depth substantially immersing the fabric container, a propeller in said tank at a point adjacent said fabric container, said propeller disposed with its axis at a tangent to the fabric container and arranged when operated to cause a continuous column of washing solution to flow through the fabric container on one side of the axis thereof, together with driving means for said propeller and fabric container for 55 driving the latter in a direction to oppose the continuous column of washing solution impelled by said propeller.

6. A washing machine comprising a perforated rotatable fabric container, a tank inclosing the fabric container, and adapted to contain washing solution, means for rotating said container in one direction and means for causing a movement of the solution in said tank along one side of said container in a direction opposite to the direction of rotation of said container.

In witness whereof, I hereunto subscribe my name this 29th day of March, A. D. 1916.

GEORGE H. MYRICK.
